Peter Stephenson of Boston, Mass.
Letters Patent No 476 Dated July 27th 1852

The schedule referred to in these Letters Patent and making part of the same

To all Persons to whom these presents shall come:

Be it known that I, Peter Stephenson of Boston in the county of Suffolk and State of Massachusetts have produced a new and original design for a medallion of Daniel Webster, and I hereby declare that the said new design is fully described and represented in the following specification and accompanying drawings, to which reference is hereinafter made.

The figures of the accompanying plates of drawings represent my new design. In Plate 1. Fig. 1. is a front elevation of the same. In Plate 2. fig. 2. is a section taken in the plane of the line A.B. fig. 1.

The head a.a. is cast in alto-relievo on the oval panel b.b. which is set in a frame c.c. ornamented with scroll or leaf.
